CLAIM

The ornamental design for an antenna for wireless tag, as shown and described.

DESCRIPTION

FIG. 1 is a front plan view of an antenna for wireless tag, showing our new design; and,

FIG. 2 is an enlarged portion view thereof, illustrating the region indicated by 2 in FIG. 1.

The broken lines in the drawings illustrate portions of the antenna for wireless tag that form no part of the claimed design. The dot-dash lines represent only the boundary between the claimed portion and unclaimed portions. All sides not shown form no part of the claimed design.
